ABSTRACT OF THE DISCLOSURE

A dental prophylaxis instrument and container for a cleaning compound adapted to be attached to a rotary dental tool and in which there is a rotary member which is eccentric in rotary motion to perform the combined functions of moving the cleaning compound into a tooth cleaning tip and vibrating the unit to cause the cleaning tip to vibrate on the tooth. A flexible coupling between the rotary dental tool and the cleaning tip affords vibratory motion of the instrument and also allows the operator to control the rate of cleaning compound discharge.

This invention relates to a dental prophylaxis instrument and, more particularly, to a power-driven unit which performs the multiple functions of feeding a cleaning compound to the teeth and imparting motion to a cleaning element.

In accordance with standard techniques in dental offices, teeth are cleaned by providing a high-speed rotary abrading or cleaning member, such as a bristle brush or a rubber cup used in conjunction with a cleaning compound, such as a pumice slurry. The compound is typically carried to the teeth by repeatedly dipping the abrading member into an individual compound container nearby. This procedure not only is time-consuming in its initial setup, but often results in splattering of the cleaning compound on the patient, the operator and the nearby equipment. Also, painful heating of the tooth surface can result.

Accordingly, it is one object of the present invention to provide an improved dental prophylaxis instrument which overcomes the above disadvantages of conventional equipment and which is capable of dispensing its own supply of cleaning compound.

Another object of the invention is to provide a dental prophylaxis instrument in which precisely metered amounts of cleaning compound can be brought to the tooth surfaces while the cleaning operation is taking place.

Still another object of the invention is to provide a dental prophylaxis instrument in which splattering is virtually eliminated and in which heating is minimized.

Still another object of the invention is to provide a dental prophylaxis instrument in which abrasive cleaning materials are effectively shielded from the bearings of the dental machinery.

Still another object of the invention is to provide a dental prophylaxis instrument which can be expendable for each patient treated, but which can, if desired, be sterilized and reused.

In accordance with the present invention, a conventional rotary driving unit, such as the hand piece of a dental drill having a rotary shaft coupling at its end, can be used to actuate a driving and feeding assembly in the form of a radially offset member arranged within a housing to impart vibratory motion thereto. In one preferred embodiment of the invention, this assembly can take the form of a helical spring which is either angled or weighted to be dynamically unbalanced, or both, so that its free end whips around within the housing, which is resiliently supported. This resilient sup-

2

port can take the form of a rubber sleeve between the housing and the hand piece of the drill.

The free end of the unit carries a tooth cleaning member, such as a flared rubber cup or brush, the center of which is in communication with the housing. A pre-determined supply of cleaning compound, such as a pumice slurry, is contained within the housing and the sleeve in amounts which are less than the total internal capacity of the unit so that when the driving and feeding assembly is rotated, it first causes most of the cleaning compound mass to fill the flexible coupling by voiding the space swept by its rotation. The operator then controls the amount of material extruded from the unit by squeezing the flexible coupling between his fingers to bring desired amounts of the material into the areas of influence of the driving and feeding assembly to be pumped out of the working end. The whipping action causes the cleaning head to vibrate laterally to clean the tooth surfaces.

The above and other features and objects of the present invention will be apparent from the following specification described preferred embodiments thereof taken in conjunction with the accompanying drawing in which:

FIGURE 1 is a view in longitudinal section showing in broken lines the conventional power-driven hand piece normally used in dental offices and showing in full lines coupled thereto a cleaning attachment formed in accordance with the present invention;

FIGURE 2 is a side view of the internal rotor of the cleaning attachment;

FIGURE 3 is a view in longitudinal section showing an expendable, or if desired reusable portion of the cleaning attachment containing its own charge of cleaning compound, in a form in which it might be received by a dental office; and

FIGURE 4 is an end view in transverse section taken on the line 4—4 of FIGURE 1 looking in the direction of the arrows.

Referring to the drawing, the invention is illustrated as embodied in a unit 10 adapted to be attached to the hand piece 11 of a conventional dental tool of the type to which drill or rotary cleaning elements are normally attached. The hand piece 11 includes an internal chamber 12 including a rotary coupling 13 adapted to receive a shaft which is to be rotated. The outer tip 14 of the hand piece forms a bearing for guiding the shaft to be rotated and, in the present invention, the rotated shaft comprises a short shaft element 15 including an inner end 15a adapted to be received in the coupling or chuck 13 and an outer end 15b adapted to carry a driving and pumping element 16 preferably taking the form of a helical spring.

The shaft sections 15a and 15b are separated by a bushing or seal element 17 which, as best seen in FIGURE 1 abuts closely against the open end of the hand piece 11 and which closely engages the shaft 15 to form a seal. Preferably the bushing or seal 17 can be held stationary while the shaft 15 rotates therein. The free or outer end of the element 16 is bent to form an angle α with respect to the axis of the shaft 15, this angle being a function of the spring constant or stiffness of the element, the relative dimensions of the parts, and degree of cleaning action desired, all as described later. This angle can be introduced under static conditions by bending or, if desired, it can come into being under dynamic conditions by dynamically unbalancing the element so that it will assume an angle when rotated.

Fitted over the free end of the pumping and driving element 16 is a housing 18 in the form of a cylindrical cup which can be formed, for example, of plastic. Carried by the free end of the housing 18 and preferably extending laterally therefrom is a soft cleaning element 19

adapted to engage the teeth and which can take the form of a rubber nozzle having a divergent or flaring tip 19a and a central channel 19b communicating with the interior of the cylindrical housing 18. The internal diameter of the housing 18 is such that when arranged coaxially with the axis of the drive shaft 14 and the hand piece 11, the pumping and driving element 16, under rotation, bears laterally against its internal wall to impart vibratory forces. Connecting the housing 18 with the hand piece 11 is a flexible sleeve 20, such as soft rubber, which is secured to the outer wall of the housing 18 and extends axially over the bushing or seal 17 to bear against the outer surface of the hand piece under the influence of its normal radial elasticity. The unstressed diameter of the flexible coupling 20 is such that it bears snugly against the seal or bushing 17 as well as the outer surface of the hand piece 11.

Referring to FIGURE 3, the expendable portion of the cleaning instrument is illustrated in the form in which it is normally furnished to the dentist with the nozzle or vibrating tip 19 carrying a removable plug 21, and with the inner end of the flexible coupling 20 folded back upon itself to form a cuff 22. A removable plug 23 is inserted in the cuff to contain a supply of cleaning compound 24, such as a pumice paste, or alternatively the end can be pinched closed, clipped or taped. To assemble the apparatus for cleaning teeth, the dentist inserts the drive element shown in FIGURE 2 with the shaft end 15a received within the end piece 11 to engage the coupling 13 and the plastic bushing or seal 17 bearing snugly against the tip of the hand piece in sealing relationship. The plug 23 is removed from the flexible coupling 20 which is slipped over the bushing 17 until the free end of the drive and pumping element 16 engages or is disposed close to the end of the housing 18. The cuff portion 22 is then unfolded and snapped over the end of the hand piece 20. The cleaning assembly is ready to use when the dentist removes the tip plug 21 from the cleaning element or nozzle 19. The volume of cleaning paste 24 within the housing is preferably so arranged that, when the drive shaft 15 is rotated (by means for example of a foot-controlled rheostat R which energizes the motor M), the pumping and driving element forms a cavity within the housing free of cleaning compound without driving significant amounts of the compound out through the tip 19.

To begin the cleaning operation, the dentist brings the tip 19a against a tooth surface and squeezes the flexible coupling 20 in the area between the seal 17 and the housing 18, thus causing a small amount of the cleaning compound to come within the space swept by the helical spring 16 to be expressed from the tip 19a. The cleaning element 19 is meantime being driven in a vibratory cleaning action on the tooth surface. Because there is no high-speed rotary peripheral velocity of the tip 19a, the cleaning compound is not thrown out by centrifugal force and splattering is avoided. The cleaning action is continued until the majority of the cleaning compound 24 has been expressed from the top 19a under the control of the finger and thumb pressure of the operator squeezing on the flexible coupling 20. The volume of cleaning compound expressed at any given time is under the control of the operator who holds the implement between the thumb and forefinger at the squeezing point of the resilient sleeve 20, with hand piece 11 of the power unit being carried in the crotch of the thumb and forefinger like a pencil. To insure the most effective control, in accordance with the invention, the helical element 16 is disposed forwardly, for the most part, of the squeezing area of the resilient sleeve 20, so that relatively few turns pick up and propel the cleaning compound at any given time. As the squeezing action compresses the sleeve against the shaft extension 15a, virtually the full charge of cleaning compound will be expelled drop by drop. In addition, it is preferred that part of the shaft 15a in the squeezing area be free of screw propelling surfaces both to avoid abrasion on the sleeve

and to afford the operator a more comfortable, less agitated finger grip.

It will be understood that the flexible coupling 20 permits the housing 18 and tip 19a to vibrate laterally in relation to the axis of the hand piece at a rate which is directly proportional to the axial rotation of the shaft 15. The lateral resilience of the spring element 16 precludes heavy jarring or hammering action of the cleaning member 19 in any direction including normal to the tooth surfaces. The seal 17 effectively prevents the abrasive cleaning compound from moving backwardly into the bearings of the hand piece 11 either through the space between the shaft 15 and the center hole in the seal 17 or through the space between the flexible coupling and the outer edge of the seal 17. Because the flexible coupling was initially folded back upon itself in a cuff before the unit was attached to the power source, that portion of the flexible coupling will be free of cleaning compound at all times.

In operation, under high speed rotation, a number of convolutions of the element 16 will be driven, due to its being bent (which in turn creates dynamic imbalance), against the wall of the housing 18 by centrifugal force to slide around the cylindrical surface to impart vibratory motion to the head end. In the drawing, the helical element is shown in an inactive position slightly spaced from the wall, although it will be understood that depending on such factors as the angle α and the spring force, one or more convolutions can touch the wall when there is no rotation. The light force applied to the instrument by the operator's hand holds the cleaning element 19 on the tooth surface against the vibratory force which could otherwise introduce a component of perceptible motion normal to the surface. The helical spring element yields to the holding force but there results a cyclically varying pressure normal to the tooth surface which is believed to augment the cleaning action. Also, the exact nature of the cyclical pressures and motions of the cleaning tip 19 against the tooth can be varied by virtue of the ability of the flexible coupling 20 to bend, creating an angle between the axis of the shaft 15a and the axis of the cylindrical housing 18. This causes heavier cyclical pressures against the tooth and diminishes the forces away from the tooth. This in turn changes the flexing characteristics of the cleaning tip and affords the operator a greater variety of cleaning characteristics or modes. The combined motions of the flared cleaning element vibrating in translation and expanding and contracting under cyclical pressure change, together with the superimposed motions of the operator's hand, all contribute to the cleaning action. In all cases, the severe heating of tooth surfaces which normally occurs with the use of rotary abrading devices is avoided.

While the invention has been described above having reference to a preferred embodiment thereof, it will be understood that it can take various other forms and arrangements within the scope of the invention. For example, rather than using an inclined helical spring, a straight but eccentrically weighted helical spring can be used, both being effectively dynamically unbalanced. Also an angularly inclined shaft portion or cam can be used and to more closely approximate the action of the helical spring, the shaft or cam can be formed of resilient material, or resiliently mounted, to avail of the dynamic characteristics and to soften vibrating action on the tooth surfaces, particularly in directions normal thereto. In such cases, inclined planes or surfaces such as screw threads can be used to propel the cleaning compound axially from the reservoir to the cleaning element. Also, various other types of cleaning elements, such as bristle brushes having hollow cores, can be used in place of the soft rubber cup 19. The invention should not, therefore be regarded as limited except as defined in the following claims.

I claim:

1. A dental prophylaxis instrument adapted to be driven by a rotary handpiece comprising a rotary core adapted

to be coupled to the handpiece and having a drive portion eccentrically disposed in rotary motion, a housing surrounding the eccentric portion of the rotary core and adapted to be driven in vibratory motion by the drive portion upon rotation of the core, a tubular flexible coupling to join the housing to the handpiece and forming a chamber for a cleaning compound, a tooth cleaning member carried by the housing and movable therewith, and means forming a passage from the chamber to the cleaning element, whereby the coupling can be manually radially compressed to express cleaning compound from the chamber and also affords relative motion between the housing and the handpiece.

2. Apparatus as set forth in claim 1, said rotary core portion including inclined surfaces to drive cleaning compound toward the cleaning member when rotated.

3. Apparatus as set forth in claim 1, said eccentrically disposed portion of the core comprising a radially resilient member.

4. Apparatus as set forth in claim 1, said eccentrically disposed portion of the core being dynamically unbalanced and radially resilient.

5. Apparatus as set forth in claim 1, said eccentrically disposed portion comprising a helical spring element coupled at one end to a rotary shaft and dynamically unbalanced at its free end to be whipped against the interior of the housing to effect vibratory excursion of the tooth cleaning member.

6. Apparatus as set forth in claim 5, said housing being circular in cross section and substantially rigid, and said tubular flexible coupling being adapted to be squeezed to bring cleaning compound into the orbit of travel of said spring element to be driven out of said chamber by the helical convolutions thereof.

7. Apparatus as set forth in claim 5, said rotary core portion including an inner shaft portion carrying said helical spring at one end and adapted to be driven in rotary motion at the other end from a handpiece, and a circular sealing member between the ends of the inner shaft within which the shaft rotates in sealing relationship and adapted to engage the tubular flexible coupling at its outer edge in sealing relationship, thereby to seal the cleaning compound from the handpiece, said sealing member being axially spaced from the rigid housing to define a flexing area affording vibrational movement of the housing and also a squeezing area to be compressed radially to urge cleaning compound into the orbit of the helical spring member.

8. Apparatus as set forth in claim 5, said cleaning element comprising a resilient member having an outwardly flaring tip portion and a central bore defining

a passage for cleaning compound and arranged adjacent the free end of the housing with its axis disposed substantially normal to the axis of rotation of the helical spring and inner shaft portion.

5 9. A dental prophylaxis instrument adapted to be driven by a rotary handpiece comprising a tubular housing having a circular interior cross section, a flexible coupling to join the tubular housing to the handpiece and a rotary core portion adapted to be driven by the handpiece and extending into the tubular housing, the rotary core including at its end within the tubular housing a cantilevered helical spring supported and rotated by its inner end and having its free end dynamically unbalanced with respect to the axis of rotation and adapted to engage the circular interior wall under centrifugal forces to vibrate the housing under resilient pressure.

10 10. As an article of manufacture, a rotary core piece adapted to pump dental cleaning compound in an axial direction and to impart radial vibration to a dental cleaning member operable in conjunction with the compound, comprising a substantially rigid inner shaft portion having an end adapted to be coupled to and driven in rotary motion by a rotary dental tool, and an elongated head portion having a flexible, radially offset cantilever-supported pumping element attached to the other end of the inner shaft portion and including inclined surfaces on said element to expel flowable cleaning compound axially with respect to the inner shaft by the whipping action of the flexible cantilever-supported element.

15 11. Apparatus as set forth in claim 10, said head portion comprising a helical spring disposed substantially coaxially with the inner shaft at the point of attachment and inclined away from the axis of the shaft at its free end.

20 12. Apparatus as set forth in claim 11 including a circular sealing disc on the inner shaft between its ends, said shaft being rotatably received therein in sealing relationship.
